UNITED STATES PATENT OFFICE

JOHN W. HULSON, OF KEOKUK, IOWA, ASSIGNOR TO HULSON GRATE COMPANY, INCORPORATED, OF KEOKUK, IOWA, A CORPORATION OF IOWA

SMOKE CONSUMER

Application filed September 13, 1928. Serial No. 305,764.

The principal object of the invention is to provide a simple and inexpensive, yet an efficient construction and arrangement of parts for injecting air into the volatile gases at the rear end of a boiler furnace, converting them into combustible nature and causing them to flash or ignite prior to escape through the stack, thereby preventing the discharge of dense smoke.

10 Another object of the invention is to provide supporting means for the air-injecting means, in the form of a bar which may take the place of the usual tie bar at the rear end of the grate, for the purpose of tying together two longitudinal finger bar supports, forming customary parts of the grate structure.

With the foregoing in view, the invention resides in the novel subject matter hereinafter described and claimed, description being accomplished by reference to the accompanying drawings.

Fig. 1 is a perspective view showing the lower side of a grate and the invention operatively related therewith.

Fig. 2 is a top plan view partly broken away.

Fig. 3 is a vertical transverse section substantially on line 3—3 of Fig. 2.

30 Fig. 4 is a vertical longitudinal section on line 4—4 of Fig. 2.

Fig. 5 is a fragmentary perspective view.

The drawings above briefly described, illustrate the preferred form of construction, 25 and while this construction will be herein specifically explained, it is to be understood that within the scope of the invention as claimed, variations may be made.

G denotes a grate structure and B has reference to a bridge wall at the rear end thereof. The grate structure G embodies the usual longitudinal finger bar supports F whose rear ends are provided with inwardly projecting lugs L customarily bolted to a "dead grate" 40 or tie bar. For this "dead grate" or tie bar, I substitute a tie bar 6 and secure it to the lugs L by bolts 7. This tie bar is formed with one or more openings such as 8, preferably elongated longitudinally of said bar, two of 45 these openings being shown. Projecting

downwardly from the bar 6 and communicating with the opening or openings 8 thereof is a Venturi tube 9, one of these tubes being shown for each of the two openings 8 in the present disclosure. Nozzles 10 for steam, or 55 other desired fluid under pressure, are provided below the Venturi tubes 9 and in axial alignment with them, so that upward blasts from said nozzles will induce an abundance of air to travel through the tubes 9 and openings 8. Provision is made above each of these openings for diffusing the air and fluid rising therethrough, said means preferably consisting of a plurality of transverse, deflecting webs 11 extending across the space circumscribed by a wall 12, said wall rising from the bar 6 around the opening or openings 8. The webs 11 extend across the opening or 60 openings 8 and are disposed at such angles as to widely diffuse the air and the fluid from the nozzles 10, as it upwardly discharges from said openings. Thus, by supplying an abundance of air into the volatile gases directly in front of the bridge wall B, these gases are 65 converted into a combustible nature and will be burned, overcoming the discharge of dense smoke.

70 Preferably, the wall 12 is of greater height at the "bridge wall side" thereof, than at its "grate side," and the upper ends of the webs 11 are inclined toward said "bridge wall side," as it has been found that by so doing, the 75 ingoing air and the like will mix more thoroughly with the volatile gases.

In the preferred construction, the wall 12 is 80 integral with the bar 6 and the Venturi tube or tubes 9 separately formed from said bar. In the present showing, the two tubes 9 are integrally joined at their upper ends to a plate 13 which is secured by bolts 14 to the lower side of bar 6, said tubes being also integrally connected by a vertical web 15 which extends between them. Projecting downwardly from this web, a lug 16 is shown, to which a support 17 for piping of the nozzles 10, is secured by bolts 18.

85 The construction shown and described is rather simple and inexpensive, is easy to install and is of exceptional advantage in the prevention of black and dense smoke dis- 100

charge. The device may either be operated continuously, or only brought into operation when throwing fresh fuel onto the fire.

I claim:—

5. 1. A smoke consumer for furnaces, comprising a Venturi tube, means for mounting said Venturi tube in a substantially vertical position, a fluid nozzle at the lower end of said tube for upwardly directing a blast of fluid therethrough to induce ascent of air through the tube, a continuous upwardly opening wall around the upper end of said Venturi tube, and a plurality of upwardly diverging webs spanning the space within said wall for 15 diffusing the air and fluid ascending through said tube.

2. A smoke consumer for furnaces, comprising a bar adapted for mounting at the rear end of a grate, said bar having an opening, a Venturi tube projecting downwardly from said bar and communicating with said opening; a fluid nozzle at the lower end of said Venturi tube for upwardly directing a blast of fluid to induce ascent of air through the tube, a continuous upwardly opening wall rising from the bar around said opening, and upwardly diverging air diffusing webs spanning the space surrounded by said wall.

3. A smoke consumer for furnaces, comprising a horizontal bar having spaced openings, spaced Venturi tubes secured to said bar and projecting downwardly therefrom in communication with said openings, a web extending between and joined to said Venturi tubes, a lug joined to and projecting downwardly from said web, a nozzle support secured to said lug, and fluid nozzles mounted on said support for directing upward blasts of fluid through said tubes to induce air to ascend through said tubes.

4. A smoke consumer for furnaces, comprising a horizontal bar having spaced openings, spaced Venturi tubes secured to said bar and projecting downwardly therefrom in communication with said openings, a web extending between and joined to said Venturi tubes, a lug joined to and projecting downwardly from said web, a nozzle support secured to said lug, a continuous wall rising from said bar around said openings, webs spanning the space surrounded by said wall and adapted to diffuse the air and fluid rising through said openings, and fluid nozzles mounted on the aforesaid nozzle support for upwardly directing blasts of fluid through said tubes.

5. In combination with a furnace grate having longitudinal finger bar supports and transverse finger bars mounted thereon; a transverse bar behind the rearmost finger bar and resting on said finger bar supports, said bar having an opening between its ends from its lower to its upper side, bolts securing the ends of said bar upon said finger bar supports, a Venturi tube secured to and pro-

jecting downwardly from said bar in communication with its opening, a nozzle at the lower end of said tube for upwardly directing fluid therethrough, a continuous wall secured to and rising from said bar around said opening, and fluid diffusing means within said wall.

6. In a smoke consumer for a furnace, a horizontal bar having an opening from its lower to its upper side, a Venturi tube secured to and projecting downwardly from said bar in communication with said opening, a nozzle for upwardly directing fluid through said Venturi tube, a continuous wall secured to said bar around said opening and projecting upwardly from the bar, and means within said wall for diffusing fluid rising therethrough.

7. In a smoke consumer for a furnace, a horizontal bar having an opening from its lower to its upper side, a Venturi tube secured to and projecting downwardly from said bar in communication with said opening, a nozzle support secured to said Venturi tube, a nozzle secured to said support for upwardly directing fluid through said Venturi tube, a continuous wall secured to said bar around said opening and projecting upwardly from the bar, and means within said wall for diffusing fluid rising therethrough.

8. In a smoke consumer for a furnace, a horizontal bar for disposition at the rear end of a grate adjacent a bridge wall, said bar having an opening from its lower to its upper side, a continuous vertical wall rising rigidly from said bar around said opening and elongated longitudinally of the bar, said wall being open at its upper portion, relatively low at its front portion and comparatively high at its back portion, and a plurality of upwardly diverging webs extending between said front and back portions of said wall and having rearwardly inclined upper ends.

In testimony whereof I have hereunto affixed my signature.

JOHN W. HULSON.
